PAPER TRIMMING AND PASTING DEVICE

Anthony Inserra, Jamestown, N. Y.

Application May 1, 1946, Serial No. 666,311

4 Claims. (Cl. 91—14)

1

This invention relates to a device for use in the practice of hanging wall or ceiling paper. More particularly, the invention contemplates provision of a device through which paper, as provided in rolls, may be passed and, during such passage, will have received a uniform coating of paste on one surface and the edges thereof trimmed to the pattern edge or as may otherwise be desired.

It is known that other devices or mechanisms of this nature have heretofore been developed. It is believed, however, that the present invention carries out the pasting and trimming operations in a novel, accurate and efficient manner, the particular advantages of the invention being made clear in the following objects and description.

It is an important object and advantage of the present invention to provide a device for properly pasting and accurately trimming paper of the type commonly applied to building walls and ceilings.

It is also an object of the invention to provide a device of the class described which, through the inclusion of adjustable trimming means, enables, as the paper passes through the device, the accurate trimming to pattern or border margins, as may be required.

Another object of the invention lies in the provision of a device of the class described in which adjustable means is provided by which to remove the trimmed margins of the paper prior to its leaving the device.

A still further object of the invention is to provide, in a device of the class described, means for accurately controlling the amount of paste that may be applied to a surface of the paper as it passes through the device.

Other objects and advantages will be more fully understood from a consideration of the following specification, taken in conjunction with the accompanying drawing; and in which

Fig. 1 is a side elevational view of a device embodying one form of the invention, parts being broken away to disclose certain of the structural details;

Fig. 2 is a fragmentary plan view of the structure shown in Fig. 1, parts of the top or cover of the structure being broken away to disclose certain of the structural details;

Fig. 3 is a fragmentary end view showing the adjustable nature of the paper roll guide and trimmer, being taken substantially as suggested at 3—3 of Fig. 1;

Fig. 4 is a fragmentary vertical sectional view

2

taken substantially on the line 4—4 of Fig. 1 and shows one of the trimmers and part of the controller for the paste applicator; and

Fig. 5 is a fragmentary view taken substantially as indicated at 5—5 of Fig. 1, parts being broken away to show one of the trim removers.

Referring more particularly to the drawing, the reference numeral 10 is employed to generally designate a device embodying one form of the invention. For the purpose of the present disclosure, the invention is shown to comprise a generally rectangular box-like container 11. This container includes base wall 12 and side walls 13 and 14 which, for convenience, in use of the container to hold a quantity of paste, may include rounded portions 16 at the juncture of the side walls with the base wall. The end walls 17 are of a height corresponding to the walls 13 and 14 and conform thereto as to contour. Attached, in any suitable manner, to the outer face of wall 13, are angle brackets 18. Each bracket includes a bearing hub 19, the opening into which is slotted, as at 21, to permit entry of the end of a rod 22 that is adapted to mount a roll of paper 23. Of course, the brackets 18 and hubs 19 are so spaced as to permit entry therebetween of the roll 23, and any means, such as adjustable collars 24, are mounted on the rod 22 and movable to properly locate and align the roll with respect to the container 11.

Also located on the wall 13 is an entry aperture for paper from the roll 23. This aperture, as may be seen in Fig. 1, is defined by a plate 26, having a lip 27. The body of the plate is attached to the inner face of the wall 13, and the lip 27 extends outwardly through a slot formed in the wall 13. A ledge 28 mounts a cutter block 29 that extends the full width of the container. The top wall of the paper aperture is formed by an angle bar 31 that extends the full width of the container, the lowermost flange being in close proximity with the lip 27 to define the actual proportions of the paper aperture, as indicated at 32. The upstanding flange 33 of the bar 31 is formed with a horizontal slot 34 that extends nearly to the end walls 17. The upper edge of the flange 33 may terminate flush with the top edges of the walls of the container 11.

A cover 36 is mounted on the container 11, being pivotally secured thereto along wall 14 by means of a pair of hinges 37. Adjacent the hinged edge, the cover is formed with a transverse opening 38, the sides of which are defined by the vertical wall 39 of the cover and an up-

turned flange 41. The aperture 32 constitutes the place of entry of paper from the roll 23, whereas the opening 38 constitutes the place of exit of the paper from the device and, for convenience, the upper edge of the flange 41 may be sharpened to constitute a place of severance of a desired length of paper as removed from the device.

It is believed advantageous to provide means for guiding the paper as it leaves the roll 23 into the entry aperture 32, and to this end, the guide members 42 are provided. Each of these guides includes a guide flange 43 and a body portion that is apertured to receive a bolt 44. The head of the bolt is located interiorly of the container, whereas the body thereof projects through the slot 34 and an opening in the guide 42. A wing nut 46 serves to secure the guide in a position determined by the direction and length of slot 34.

A pair of trimmer members are mounted in the container 11, each including an angle plate 47, having a stud projecting through slot 34 to the exterior of the container and engaged by a wing nut 48 or its equivalent. Attached to the flange 49 of the plate 47, by means of a screw 51, is a swivel plate 52. The free end of plate 52 mounts a rotatable trimmer blade 53. In order that the blade 53 may at all times contact paper from the roll 23 as it passes over the cutter block 29, means is provided in the form of a spring 54 which is secured to the top surface of flange 49 and, extending beyond this flange, contacts a pin 56 carried by the plate 52. It is evident that by loosening wing nut 48 and moving the cutter structure just described in the plane determined by slot 34, paper from the roll 23 may be cut to any desired width within the container 11. Attached to the end walls 17 are brackets 57 which include portions that serve to mount a transversely disposed roller 58. This roller aids in determining the path of travel of the paper as it passes through the container. Also mounted in the container is a paste applicator that takes the form of a large roller 59. The axis of rotation of this roller is provided by stub shafts 61 which are seated in upwardly opening bearings 62 carried by the end walls 17. As may be seen in the drawing, the paste roller 59 is of large proportions and extends well towards the bottom of the container 11, as well as up to, or into that portion of the container defined by the cover 36. It will also be noted that the roller 58 is in close proximity with roller 59.

A shaft 63 extends transversely of the container 11 through the end walls 17. The external ends of this shaft have keyed thereto ends of members 64. The other ends of these members are slotted, as at 65, and studs 66 secured to the side walls project through slots 65 and are engaged by suitable wing nuts 67. The shaft 63 carries a block 68 to which is attached a cleaner blade 69. This blade projects beyond the block 68 into close proximity with the surface of roller 59. It will be understood that paste of such consistency as to be properly applicable to wall-paper is intended to be located in the lower part of the container 11, and the roller 59 is in part submerged therein. As this roller rotates in a direction indicated by the arrow A, paste adheres to the roller surface. The amount of paste applicable to a surface of the paper as it passes between rollers 58 and 59 may be accurately controlled by adjusting the blade 69. Adjustment of this blade is, of course, accomplished by rotation of shaft 63 through the members 64. A further roller 71 is positioned transversely within

the container 11, being mounted in suitable bearings 72 carried by the end walls 17. This roller is in close proximity with the surface of roller 59 at a point adjacent the hinged edge of the cover 36. The wall 14 is formed with a transversely extending slot 73, the lower edge of this slot being defined by an inturned flange 74. The flange 74 is also slotted, as at 76, for the purpose of mounting and permitting adjustment of a pair of trim removers 77. These trim removers may be secured at any point throughout the length of the slot by screws 78, and each includes a laterally and vertically offset finger 79. Each finger 79 projects toward and into contact with the roller 15 71.

In operating the above described device, it is first necessary to fill the container 11 with suitable paste to a level slightly below the bearings 62 of the roller 59. This, of course, is done with 20 the cover 36 in fully opened position. While the cover is so positioned, a roll of paper 23 is mounted on the brackets 57. The paper is so positioned that the pattern thereon is uppermost and the end of this paper is fed into the entry 25 aperture 32, being moved over the cutter block 23, between rollers 58 and 59, over the upper surface of roller 59, thence around roller 71 and out through the opening 38 of the cover 36. Following this, the guides 42 are adjusted to properly 30 center the paper as it enters the container, and the cutters are adjusted to be effective along the marginal edges of the paper. Practice in use of the device, as well as the consistency of the paste and the quality of the paper, will determine the 35 proper position of the scraper blade 69 with respect to the roller 59. It is evident from the foregoing that as the free edge of the paper, extending out of the container from opening 38, is grasped and pulled, paper from roll 23 will feed 40 through the device, causing roller 59 to rotate. Thus, as paper is withdrawn, it has been cut to the desired margin by the cutters 53 and the trimmed edges, as well as the paper itself, have moved up and over roller 59. However, since the 45 trim removers 77 have been adjusted to the same spacing as the cutters 53, the fingers 79 thereof will cause the cut trim to pass outwardly of the container through the slot 73 while the paper proper passes around roller 71 and out of the 50 container through opening 38.

Although applicant has shown and described only one modification of the invention, it will be apparent that the general proportions of the structure may be modified without departing from the spirit and scope of the invention as set out 55 in the annexed claims.

Having thus set forth my invention, what I claim as new and for which I desire protection by Letters Patent is:

1. A device of the class described comprising a container having an external paper roll support, a cover on said container, one wall of said container being formed with a slot to provide a restricted paper entry to said device, adjustable means for guiding paper into said slot, edge trimmer members mounted in said container adjacent said slot, a series of parallel rollers determining a path of travel of paper passing through said device, the cover of said container including a slot to provide a paper exit from said device, and means for removing trimmed portions prior to the exit of paper from said device.

2. A device of the class described comprising a container having an external paper roll support, a cover for said container, one wall of said con-

tainer being formed with a slot to provide a paper entry to said device, adjustable means for guiding paper into said slot, adjustable edge trimmer members mounted in said container adjacent said slot, a series of proximate parallel rollers in said container, one of said rollers constituting a paste applicator, means adjustable to control the amount of paste applicable by said one roller to any given paper, the cover of said container including a slot to provide a paper exit from said device, and means adjacent said exit slot for separating the trimmed portions from the paper and directing said portions from said device at a point remote from said paper exit.

3. A device of the class described comprising a container having an external paper roll support, a cover for said container, one wall of said container being formed with a slot to provide a paper entry to said device, adjustable means for guiding paper into said slot, edge trimmer members adjacent to and adjustable in the direction of the length of said slot, a cutter board forming a continuation of one wall of said slot, means yieldingly engaging said trimmer members with said board, a series of parallel rollers in said container determining a path of travel for paper passing through said device, one of said rollers serving as a paste applicator, means remote from said entrance slot for removing trimmed portions through an opening in a vertical wall of said container, and the cover of said container being slotted to provide a top exit for the paper.

4. A device of the class described comprising a closed container having an external paper roll support, one wall of said container being formed with a slot to provide a paper entry to said device, adjustable means for guiding paper into said slot, edge trimmer members mounted in said container adjacent said slot, a series of parallel rollers in said container determining a path of travel for paper passing through said device, one of said rollers serving as a paste applicator, adjustable means for determining the amount of paste applicable by said one roller to any given paper, one wall of said container including a slot to provide a paper exit from said device, another of said rollers being located adjacent said exit slot, and adjustable means engageable with said other roller for removing the trimmed portions of said paper prior to its exit through said one wall.
